CAR ROOF

David W. Hawksworth, Birmingham, and Alfred R. Wilson, Detroit, Mich., assignors to Hutchins Car Roofing Company, Detroit, Mich., a corporation of Delaware

Application June 1, 1931. Serial No. 541,504

6 Claims. (Cl. 108—5.8)

The invention relates to car roofs of the type known as universal in which roofing elements of standard form and dimensions can be applied to cars having roofs of different areas. To apply 5 such roofing elements to cars of different widths, provision is made for an overlapping joint which is adjustable transversely of the car to extend or contract the roof. Adjustment to different lengths of cars may be made in various ways, but 10 preferably this also is by the provision of overlapping adjustable roofing elements at one end of the car. However, due to the fact that the roof must also be adjustable in width as well as in length, certain complications arise which render it difficult to obtain a thoroughly practical 15 and weatherproof construction.

It is the object of the present invention to obtain a construction which permits of variably adjusting the roof longitudinally of the car to an 20 extent substantially equal to the width of one of the roofing sheets and which is also adapted to form a thoroughly weatherproof construction in all positions of adjustment, and one which is securely fastened down on the car frame. To this 25 end the invention consists in the construction as hereinafter set forth.

In the drawings:

Figure 1 is a plan view of a portion of a car roof embodying my invention;

Figure 2 is a longitudinal section in the plane of the ridge;

Figure 3 is an end elevation of a portion of the end transverse cap;

Figure 4 is a side elevation thereof;

Figure 5 is a section on line 5—5 of Figure 4;

Figure 6 is a perspective view partly broken away showing the construction of the adjustable end transverse cap and cooperating elements.

The roof frame may be of any suitable construction but as shown comprises the carlines A and purlines B. Supported on this frame are roofing sheets C which extend on opposite sides of the ridge to the eaves, being provided on opposite side edges with the upstanding flanges D terminating in laterally extending flanges D' which overlap the carlines. These side flanges are continuous with an upstanding flange E at the ridge end of the sheet and at the eaves are downwardly extending return bent portions F which have a weatherproof engagement with a flashing G. This flashing is preferably formed of a strip of Z cross section having the portion G' which is nailed to the side plate of the car, the outwardly extending web G² and the down-turned flange G³, which latter engages the re-

turn bend of the roofing sheet. Between adjacent sheets on opposite sides of the carline are weatherproofing caps H which bear down on said sheets to form a weatherproof joint and to also retain the sheets upon the roof. These caps H are held down near the eaves by bolts I and at the ridge are held down in the usual manner by ridge caps J and junction caps K which caps are of sufficient width to permit of adjustment of the sheets C thereunder to correspond to different widths of cars.

The construction as thus far described has heretofore been used as a universal roof for application to cars of various widths, the same standard elements being used in each case with only a difference in the amount of overlap of the ridge cap on the sheets. Where, however, the car is different in length by an amount which is less than the width of one sheet, this requires a construction capable of longitudinal as well as transverse adjustment. Here a difficulty arises due to the fact that the longitudinal adjustment means must be engageable with the other elements of the roof in all different adjustments for different widths of cars. Thus in one extreme the roofing sheets C on opposite sides of the ridge are arranged with their ridge flanges E in close proximity while in the other extreme these flanges are widely separated and are arranged in close proximity to the opposite sides of the ridge cap J. To overcome this difficulty we have devised a construction of transverse cap for use at the end of the car which is adapted to variably overlap the adjacent roofing sheet while at the ridge there is provided a cap of special construction adapted to form a weatherproof joint with both the end transverse caps and with the adjacent ridge cap without interfering with the adjustment of the roof to various widths of cars, the construction being as follows:

The end transverse cap L is formed of a width sufficient to provide for the necessary adjustment longitudinally of the car for variation in length of cars less than the width of one of the sheets C. This cap L has the downturned flange L' overlapping the end of the car and rigidly secured thereto by nailing as indicated at L². The length of the cap transversely of the car is not, however, as great as the length of the caps H and is so restricted that even for minimum widths of cars the ridge ends of said caps L do not extend beyond the side flanges of the ridge cap. This will permit the caps L to longitudinally overlap the ridge cap J without interference therewith. In place of the usual construction of junction cap, a

cap M is provided, having a downturned flange M' nailed or otherwise rigidly secured to the end of the car and being of a width corresponding to the width of the caps L and of a length transversely of the car greater than that of the ridge cap and junction caps. This greater length is sufficient to maintain a weatherproof joint with the short end caps L even where the roof is adjusted for cars of maximum width and as the cap M also fits over the ridge cap J and is adjustable theron, the construction can be placed on cars differing both in length and width and will form a weatherproof joint in each instance.

To hold the caps L down at the eaves it is not possible to use the construction of bolts I, such as are used with the transverse caps H, for such bolts would interfere with the end sheet C' in different positions of adjustment thereof. We have therefore devised a construction of holding down means at the eaves permitting freedom for adjustment and at the same time maintaining a thoroughly weatherproof joint, the construction being as follows: The caps L have at the eaves downturned flanges L³ which terminate in return bent flanges L⁴, the width of the return bends being greater than that of the return bends F of the sheets C. As has been described, the return bends F of the sheets C form a weatherproof engagement with the downturned flange G³ of the flashing G, which flashing has the laterally extending web portions G² and the flange portion G' which is rigidly secured to the side plate of the car. To hold down the caps L there is provided a U-shaped member N which embraces the return bend portions L⁴ and has one leg N' extending upward to engage the under side of the web G². O is a bolt having a T head O' engaging a recess L⁵ in the return bent flange L⁴, said bolt passing downward through an aperture in the U-shaped member N and being provided with a clamping nut P. Thus by tightening the nut P the return bent flange L⁴ may be drawn downward, the reaction being taken by the U-shaped member N which is anchored by the bearing of the upper end of the leg N' against the flashing G. As this flashing is securely fastened to the car frame it is evident that the tightening of the nut P will draw the cap L down upon said frame and will maintain a weatherproof joint between the cap and the sheet C'. The member N is preferably formed of relatively heavy gauge metal so as to have the requisite strength, and the upper end of the leg N' is return bent at N² to form a bearing on the web G² fairly close to the plane of the flange G'. The T head O' of the bolt O being in the recess or depressed portion L⁵ of the return bend L⁴, will not interfere with the free longitudinal movement of the return bend F thereover. A lock washer Q may be placed between the nut P and the member N with a flange Q' thereof which may be bent down to hold the nut from disengagement.

As the roof is of the flexible type it is desirable to prevent interference with the relative movement of the sheets and cap by the holding down means. This is accomplished first by forming the head O' of the bolt of segmental cylindrical form which permits the rocking of the bolt in relation to the U-shaped flange; second, by avoiding any fixed attachment between the member N and the flashing G² so that said member N is free to move longitudinally relative to said flashing.

What we claim as our invention is:

1. In a car roof of a type adjustable to fit cars of different lengths and widths, the combination

with roofing sheets arranged upon opposite sides of the ridge having upstanding side and ridge flanges, and ridge caps embracing said ridge flanges and overlapping said sheets to provide for adjustment of the same to different widths of cars, of an end-transverse cap embracing the side flange of the adjacent sheet and adapted to variably overlap said sheet, the length of said end cap being less than the length of said sheets to clear said ridge cap when adjusted to minimum widths of cars, an end junction cap fitting over said ridge cap and adjustable longitudinally thereof, said end junction cap being of greater width than said ridge cap to overlap said end-transverse cap when adjusted for maximum width of cars and means for holding down said end transverse cap at the eaves permitting a variable overlapping engagement of said cap with the adjacent sheet, and maintaining weatherproof joint in all positions of adjustment.

2. In a car roof of a type adjustable to fit cars of different lengths and widths, the combination with roofing sheets arranged upon opposite sides of the ridge having upstanding side and ridge flanges, and ridge caps embracing said ridge flanges and overlapping said sheets to provide for adjustment of the same to different widths of cars, of an end-transverse cap embracing the side flange of the adjacent sheet and adapted to variably overlap said sheet, the length of said end cap being less than the length of said sheets to clear said ridge cap when adjusted to minimum widths of cars, and said cap being provided with a down-turned end flange rigidly attached to the end of the car, an end junction cap having a downturned end flange, rigidly attached to the end of the car, said cap embracing said ridge cap to variably overlap the same longitudinally thereof, and being of a length transversely of the car in excess of the width of said ridge cap to engage said short end-transverse cap when adjusted for maximum widths of cars, and means engaging said end-transverse cap at the eaves for holding down the inner edge of said caps upon the adjacent roofing sheet to maintain a weatherproof joint, said means avoiding interference with the relative adjustment of said sheet and cap.

3. In a car roof, the combination with roofing sheets having downturned return bent eaves flanges and a flashing secured to the side of the car having a depending flange engaging the return bend of said sheets, of an end-transverse cap for variably overlapping the adjacent roofing sheet, said cap having a downturned flange for rigid attachment to the end of the end of the car and a return bent eaves flange for embracing the return bent flange of the roofing sheet and a holding down means for said cap comprising a bolt engaging the return bent eaves flange thereof, a nut on said bolt and an abutment for said nut anchored to said flashing.

4. In a car roof, the combination with roofing sheets having downturned return bent eaves flanges and a flashing secured to the side of the car having a downturned flange engaging said return bent flanges, of a weather-proofing cap for said sheets also provided with downturned return bent eaves flanges embracing the corresponding flanges on said sheets, a bolt having its head engaging a depressed portion in the return bent flange of said cap to clear the return bent flange of said sheet, said bolt extending downward from said cap, a U-shaped abutment member embracing said return bent flange of

5 said cap and apertured for the passage of said bolt therethrough, one leg of said abutment member having an anchorage engagement with said flashing and a nut for engaging said bolt and 5 said abutment to draw said cap down upon said sheet.

10 5. In a car roof, the combination with roofing sheets having downturned return bent eaves flanges and caps for said sheets having corresponding downturned return bent flanges telescopically engaging the flanges of said sheets, of 15 a flashing secured to the car body and having a downturned flange engaging the return bent flanges of the caps and sheets, and a holding down means for a cap comprising a bolt having a T-head of segmental cylindrical form rockably 20 engaging a depressed portion of the return bent flange of said cap, said bolt passing through a slotted aperture in said return bent flange, a U-shaped abutment member embracing the return bent flange of said cap and having one leg extending upward into contact with said flashing, and a nut engaging said bolt and bearing against

said abutment to draw said cap downward upon the sheet.

6. In a car roof, the combination with roofing sheets having downturned return bent eaves flanges, and a cap for said sheets provided with a corresponding downward return bent eaves flange embracing the flange of said sheet, a Z-bar 80 flashing having one flange rigidly secured to the car body, and the parallel flange engaging the return bent flanges of said sheets and cap, and a holding down means for said cap comprising a bolt having a T-head engaging a depressed recess in the return bend of said cap to avoid interference with the return bend of said sheet, said bolt passing through a slotted aperture in said 85 cap to be rockable in relation thereto, a U-shaped abutment member embracing the return bend of said cap and having one leg extending upward into contact with the web portion of said Z-bar flashing and a nut for engaging said bolt and 90 abutment for drawing the cap downward on the sheet.
